CASING FOR PHOTO PRINTING MACHINE

Joel W. Bravo, Binghamton, N.Y., assignor to General Aniline & Film Corporation, New York, N.Y., a corporation of Delaware

Filed June 26, 1963, Ser. No. 75,531

Term of patent 14 years

(Cl. D61—1)

FIG. 1 is a front perspective view of a casing for photo printing machine showing my new design;
FIG. 2 is a rear perspective view thereof.

I claim:

The ornamental design for a casing for photo printing machine, substantially as shown.
